UNITED STATES PATENT OFFICE.

CHARLES B. MOORE, OF EVANSTON, ILLINOIS, ASSIGNOR TO AMERICAN ARCH COMPANY, OF NEW YORK, N. Y., A CORPORATION OF NEW YORK.

LOCOMOTIVE-BOILER FURNACE.

1,115,231.

Specification of Letters Patent.

Patented Oct. 27, 1914.

Application filed December 18, 1911. Serial No. 666,340.

To all whom it may concern:

Be it known that I, CHARLES B. MOORE, a citizen of the United States, and a resident of Evanston, Cook county, Illinois, have invented certain new and useful Improvements in Locomotive-Boiler Furnaces, of which the following is a specification.

My invention relates to improvements in locomotive boiler furnaces and has particular reference to improvements in refractory baffles, deflecting walls or arches for locomotive fireboxes.

The general objects of my invention are to provide an improved refractory arch which 15 may be easily and quickly installed in locomotive boiler fireboxes; to provide an arch which shall be comparatively light and yet of sufficient strength to properly maintain itself in position when once placed; to provide an arch which shall be adapted for easy 20 repair and the parts of which may be removed to afford easy access to the firebox sides and flue sheet; and to provide an arch of such construction that it can be readily 25 adjusted to the dimensions of the firebox within which it is being built.

A special object of my invention is to provide an improved arch of the character hereinafter outlined which shall be adapted for use in 30 locomotive fireboxes that are equipped with arch supporting or water circulating tubes.

Still further objects of my invention will appear hereinafter.

My invention consists in the several improvements, the various constructions and the combinations of parts hereinafter set forth and particularly pointed out in the claims, and it will be readily understood by reference to the accompanying drawings in 40 which I have illustrated a structure which, in a preferred form, embodies the several features of my invention, together with a structure which illustrates a slight modification of my invention.

In the drawings, which form a part of the specification: Figure 1 is a central longitudinal section of a locomotive firebox equipped with a refractory arch embodying my invention in one form; Fig. 2 is a detail horizontal section of the firebox on the line 2—2 of Fig. 1, showing arch in plan; Fig. 3 is a vertical transverse section of the firebox on the line 3—3 of Fig. 1; Fig. 4 is a detail transverse section of the arch on the line 4—4 of Fig. 2; Fig. 5 is a fragmentary longitudinal

section of a firebox showing a slightly modified form of the invention; Fig. 6 is a fragmentary view similar to Fig. 2 showing a top plan view of the arch as illustrated in Fig. 5; and Fig. 7 is a detail transverse section of the modified form of arch on the line 7—7 of Fig. 5.

My invention may be embodied in arches of varying details of construction and location in the firebox and although I have illustrated my invention as applied to the construction of a so-called front arch, it should be understood that my invention is not limited to the particular location or function of an arch of this character.

A locomotive boiler firebox as shown in the drawings consists of a flue sheet 2, side sheets 3, 3, a rear sheet 4 and a crown sheet 5. The box is provided with the usual grate 6. Flues 7 lead forward from the flue sheet 75 and the rear sheet is provided with a door or fuel opening 8. Water circulating tubes 9 extend rearwardly and upwardly from the flue sheet to the rear sheet and serve to increase the circulation of water between the 80 front and rear water legs of the boiler.

A so-called front arch serves the purpose of obstructing the direct flow of the gases and products of combustion from the fuel bed to the flues and causes them to zig-zag 85 back and forth in the firebox, thereby not only retaining them within the firebox for sufficient time to complete the combustion of the fuel particles before they escape through the flues, but also causing the hot gases to 90 distribute their heat evenly throughout substantially the whole interior surface of the firebox and particularly throughout the length of the crown sheet.

A particular object of my invention is to 95 improve the construction of front arches so that they can be quickly and easily placed in position; furthermore, so that with substantially one form of brick, arches can be built in fireboxes which vary considerably 100 in width.

The firebox illustrated is provided with two of the water circulating tubes 9, arranged symmetrically therein; that is, at equal distances from the center, and in fireboxes thus equipped I preferably form or build my arch of bricks 10 and 12 which are substantially flat, rectangular slabs of refractory material. These slabs are limited 105 in size by the features that they shall not be 110

of such large dimensions but that they can be readily passed through the fire door into the firebox and further by the feature that they shall not be too heavy to be handled 5 with ease and placed in position, and they the firebox and further by the feature that they shall be long enough to span from tube to tube and rest securely upon the tubes at their ends. These bricks 10 and 12 are made 10 of such a thickness that they have sufficient strength to carry their own weight and the arch, as I construct it, consists of a middle portion made up of a plurality of these bricks 10 placed upon the tubes parallel with 15 and adjacent to each other and which extends from the flue sheet rearwardly to substantially the middle of the firebox. The transverse ends of these bricks 10 are cut away on their upper sides substantially to 20 half the thickness of the brick, whereby these bricks are provided with transversely projecting ledges 11 and a vertical shoulder 11' and to complete the arch I provide marginal or side bricks 12 formed upon one end 25 substantially identical with the ends of the center bricks 10; that is, they are cut away upon one surface substantially half the thickness of the brick thereby forming projecting tongues 13 which are half the thickness 30 of the brick and are adapted to rest upon the ledges 11 of the bricks 10. The end 14 of the tongue 13 is thus brought into position adjacent to the shoulder 11' of the bricks 10, and these marginal bricks extend 35 from the center bricks to the side sheets of the firebox where they are supported by lugs or other suitable supports 15 secured upon the side sheets. The bricks 12 are substantially the same dimensions as to 40 thickness and width as the center bricks and the arch as completed comprises a plurality of rows of bricks extending from side sheet to side sheet supported at the ends by the lugs 15 and at the middle portion by 45 the tubes 9. This formation of the overlapped adjacent ends of the bricks 10 and 12 provides a construction by means of which the length of the individual rows of bricks can be varied and consequently the 50 width of the arch as a whole can be varied as the marginal bricks can be positioned in relation to the center bricks with the ends 14 of the tongue 13 in contact with the shoulder 11' or at a distance therefrom, the 55 only necessary feature being that the projecting tongues of the two bricks overlap sufficiently to support the marginal bricks in proper position.

In building arches according to my invention, I first place one of the center bricks 10 upon the lower ends of the circulating tubes and adjacent to or in contact with the flue sheet. The cut-away portions of the 65 ends of this brick are on its upper side in position to receive and support the inner

ends of the marginal bricks and I complete this lower portion of the arch by placing one of the marginal bricks on each end of the center brick supporting the outer ends of the marginal bricks upon the side sheets. 70 As shown in the drawings, these marginal bricks are short enough to provide a space 16 between their inner ends 14 and the shoulders 11' of the center bricks and in order to prevent the marginal bricks from moving transversely in the firebox under ordinary conditions, I fill this opening 75 preferrably with some kind of filler material such as sand which will not fuse and cement the bricks into a solid structure. After having placed the first row or line of bricks extending 80 from side sheet to side sheet, I complete the arch by adding further transverse rows of the bricks in like manner, the center brick resting upon the tubes and the marginal 85 bricks resting upon the center brick and upon the lugs or brick supports provided on the side sheets. While in some instances two transverse rows of the fire bricks are sufficient to accomplish the results desired 90 in the deflection and admixture of the firebox gases, it usually requires a further number of transverse rows of bricks and usually the arch extends rearwardly to approximately the middle portion of the firebox. 95

In some instances it is desirable to provide an arch of a lighter form of construction than that which has been described, either on account of the weight of an arch of this character being too great to be properly supported by the tubes or for some other reason, and in such cases I build an arch of lighter weight, as illustrated in Figs. 5, 6 and 7. In this modified form of arch, instead of having the transverse rows 100 of bricks placed upon the tubes adjacent to and in contact with each other, I space them apart longitudinally upon the tubes and hold them in this spaced relation by means of light cover or panel bricks 17. These 105 panel bricks are quite thin and are adapted to rest upon and be supported by the span bricks and are provided on their under sides with projections 18 which form shoulders 19 for contact with the sides of the span 110 bricks. I make these cover bricks of such a size that a number of them are necessary to fill in from one side sheet to the other and they not only serve to hold the span bricks in spaced relation, but they also fill the 115 space between the span bricks and thus complete the arch. An arch formed in this manner is considerably lighter than the preferred form of arch, for although it may be necessary to make the span bricks slightly 120 thicker in order that they may be strong enough to carry their own weight and the weight of the cover bricks, still the arch as a whole can be considerably lightened. This 125 modified form of arch not only provides an 130

arch construction by which arches may easily be installed in fireboxes of different widths, but as the cover bricks do not extend from the upper surface of the span bricks to their lower surface, they provide transverse deflecting grooves 20 and transverse deflecting walls 21 on the under surface of the arch, which serve to materially increase the efficiency of the arch in the function of deflecting the products of combustion and effecting the commingling and intermixing of the various strata of gases.

Being made up of small units or members my arches may be made up or taken down with little expenditure of time and labor. Another advantage pertaining thereto is that the comparatively small, light marginal bricks may be easily removed when work is to be done upon the side sheets 20 or the flue sheet or the stay bolts of the firebox without disturbing the other parts of the arch. Two other advantages inherent in this construction of arch are that the arch is to a considerable degree flexible; 25 that is, being composed of parts which have small areas of opposing contact one with another, it readily adjusts itself to the walls of the firebox or any movement thereof which is occasioned by variations of temperature, and second, the joints formed by the overlapping portions do not cement to the extent which causes the ordinary arch soon to become a substantially rigid mass or structure and therefore the arch is not 30 subject to the deteriorating effects due to the expansion and contraction of the firebox and furthermore, in this form of arch construction as the marginal bricks are movable from and toward the center bricks, 35 they are free to be forced toward the center brick at times when the firebox becomes narrower in width due to a change of temperature, and the infusible material with 40 which the grooves are filled will give way 45 under this pressure and permits this movement.

Although I have herein shown supporting bricks or spans supported upon two parallel arch tubes, it is obvious that my invention admits of other arrangements of arch tubes and that the arrangement of the bricks in the arch can be readily changed to comply therewith and that the specific construction of the arch can be modified 55 considerably without departing from the spirit of my invention. Therefore, I do not confine the invention to the specific construction herein shown and described.

I claim:

1. A locomotive boiler furnace containing a plurality of parallel arch tubes, in combination with a refractory arch therein, comprising a plurality of slab-like bricks arranged substantially in a single plane, said arch being compressible transversely of the

firebox to accommodate itself to variations in width of the firebox due to changes of temperature and comprising a plurality of transverse rows of slab-like bricks supported by said tubes and by arch supporting devices carried by the side sheets, each of said transverse rows comprising a middle brick and two end bricks aggregating in total length greater than the width of the firebox and having overlapping end portions of substantially half the thickness of the bricks whereby the bricks are adapted to lie in a single plane, the end bricks being movable from and toward the side sheets and when positioned in contact with the side sheets providing grooves in the upper surface of the arch between their inner ends and the body of the center brick, and non-fusible material filling said grooves and permitting the side bricks to be forced inwardly toward the center bricks at times when the firebox contracts in width.

2. A locomotive firebox containing a plurality of arch tubes, in combination with a refractory arch supported by said tubes and extending from side sheet to side sheet, said arch comprising a plurality of flat refractory members lying substantially in a single plane and arranged longitudinally in the firebox, and consisting of a center portion and two side portions each thereof being flat and the three being arranged in a single plane, the inner edges of the side portions overlapping the lateral edges of the middle portion and said overlapping edges being cut away on their adjacent faces whereby the arch is of substantially the same thickness at these overlapped portions as in other parts, arch supporting lugs carried by the side sheets arranged to support the outer edges of said outer portions of the arch, said outer portions of the arch being movable from and toward the center portion in the plane of the arch and when placed in contact with the side sheets of the firebox forming longitudinal grooves in the upper surface of the arch between the inner ends of the said portions and the body of the middle portion, and compressible non-fusible material in said grooves which permits the side portions to be forced toward the middle portion at times when the firebox contracts in width.

3. A transverse refractory arch for locomotive boilers comprising a plurality of transverse rows of several refractory bricks each of which extends from side sheet to side sheet, the bricks of the arch lying substantially in a single plane, the adjacent ends of the bricks in each row overlapping each other and the effective length of the row being less than the width of the firebox, thereby permitting the bricks to be placed in position in their normal plane and then spread apart transversely of the firebox to fit snugly

- 4
- between the side sheets, and non-fusible material between the adjacent ends of the bricks yieldingly maintaining the end bricks in contact with the side sheets.
- 5 4. In a refractory arch for locomotive boilers, a transverse row of several slab-like bricks arranged in a single plane their ends overlapping, and said row extending from side sheet to side sheet, the overlapped ends
- 10 being formed to permit the longitudinal adjustment of the bricks to the dimensions of the firebox, means for supporting said bricks in said position, and means for yieldingly maintaining the end bricks against the side
- 15 sheets.
5. In a locomotive boiler firebox a refractory arch supported therein and extending

from side sheet to side sheet, said arch being provided with a plurality of overlapping adjustable joints whereby the width of 20 the arch can be made to correspond with the width of the firebox, and whereby the necessary adjustment can be divided between the several joints, and means for maintaining the parts of the arch in their adjusted 25 positions.

In testimony whereof, I have hereunto set my hand, this 5th day of December, 1911, in the presence of two subscribing witnesses.

CHARLES B. MOORE.
